PLIER TYPE STAPLING MACHINE

Fridolin Polzer, South Norwalk, Conn.

Application November 10, 1934, Serial No. 752,491

8 Claims. (Cl. 1—49)

This invention relates to new and useful improvements in stapling machines and has particular relation to a plier type stapling machine of the kind used for stapling together various articles, such for example as sheets of paper and the like.

An object of the invention is to provide a stapling machine of the character stated which includes improved features of construction whereby the machine has long useful life.

Other objects and advantages will become apparent from a consideration of the following detailed description taken in connection with the accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:—

Fig. 1 is a side elevational view with parts broken away, showing the improved machine with the parts in their normal positions;

Fig. 2 is a view partly in elevation and partly in section and on an enlarged scale, showing the operating parts in their normal positions;

Fig. 3 is a view somewhat similar to Fig. 2 but on the scale of Fig. 1 and showing the position of the pivoted staple supporting housing on initial movement of the handle to drive a staple;

Fig. 4 is a similar view showing the positions of the parts during the final clinching of a staple;

Fig. 5 is a sectional view taken substantially along the line 5—5 of Fig. 2;

Fig. 6 is a side elevational view with parts broken away showing the head portion of the staple supporting housing;

Fig. 7 is a sectional view taken along the line 7—7 of Fig. 6;

Fig. 8 is a side elevational view showing on an enlarged scale the two parts of the head of Fig. 6 before assembly;

Fig. 9 is a top plan view of the head of the staple supporting housing; and

Fig. 10 is a perspective view of a plunger employed.

Referring in detail to the drawings, the improved stapling machine as shown includes a main housing or body 10 comprising side walls 11 and 12, a top wall 13 and a bottom wall 14. This housing 10 may be a die casting as shown or may be made up of sheet metal or the like as desired. The side walls 11 and 12 of the housing 10 are cut away to provide a mouth or notch 15

opening inwardly from the machine and into which papers or the like 83 (Fig. 4) to be stapled together, may be inserted. Disposed on the bottom wall 14 of the housing at the lower side of the notch 15 is an anvil bar 16 secured in place as by means of screws or the like 17. In its upper side adjacent its forward end the bar 16 is provided with anvil recesses 18 which bend or fold the prongs of staples against the underside of the papers being stapled and thus clinch the staples 10 in the usual manner after their prongs have been forced through the papers.

Disposed within the main housing 10 is a pivoted or movable staple supporting housing or magazine generally designated 19. This housing 19 may also be formed as a die casting and includes an elongated hollow body 20 at its forward end provided with an upward extension 21 comprising a portion of a head generally designated 22. Within the elongated body 20 is a staple guide bar 23 generally U-shaped in transverse section as best shown in Fig. 7, and arranged to be straddled by a strip of staples 62, which staples are to be fed to the head 22 and driven therefrom one at a time as will later appear. At the forward end of the guide bar 23 there is arranged a shear block 24, and the housing 20 includes a top wall 25 spaced above the upper edges of the guide bar a distance sufficient to permit of the passage of the connecting portion of a staple, as will be understood.

The upward extension 21 at the forward end of the elongated body 20 is closed at its forward side as by a wall 26 and through its rear side is provided with a slot 27. Intermediate its forward and rear sides it is provided with a pair of vertically extending dividing or partitioning pieces 28 projecting toward one another but having their adjacent vertical edges spaced apart as shown best in Fig. 9. The partitioning extensions 28 together with the rear or inner wall 29 of the extension 21 provide a vertical guideway 30 in which is operable a plunger 31. This plunger comprises a blade-like body 32 bifurcated in its lower portion or provided with a slot 33 and having an opening 34 in its upper portion. If desired, the upper portion of the body 32 may be reinforced or stiffened as by securing thereto a relatively heavy plate 35 which plate as here shown is secured to the body 32 by a rivet 36. The thickness of the upper portion of the plunger 31 is equal to the width of the guideway 30, so that the plunger is vertically movable in the guideway but has no other loose movement therein.

The staple guide bar 23 extends beyond the forward end of the elongated body 20 as shown best in Fig. 8, and the forward or outer face of the shear block 24 is flush with the inner or rear wall of the guideway 30. At the lower side of its forward end the guide bar is provided with a depending lip 37 and above the projecting forward end portion of the guide bar the side walls of the housing 19 are recessed as at 38 and an opening 39 is provided through the housing. A removable part or block 40 receives the projecting forward end of the staple guide bar 23 and comprises the lower portion of the head 22, and this part 40 includes a bottom wall 41, side walls 42 and 43 and a front or forward wall 44. This block 40 closes the forward end of feed passage for the staple strip on the guide bar 23 and forms the forward wall of the lower portion of the plunger raceway 53. If a staple should become jammed 5 in the raceway so that it could not be otherwise removed, it can be released by removing block 40. Within the forward portion of the part 40 are a pair of spaced blocks 45 and between said blocks there is arranged a dog 46 pivoted as at 47. 10 Screws or the like 48 together with the pivot 47 secure the blocks in place and the screws enter from opposite sides of the part, each screw secures one block 45 and the ends of the screws do not enter into the space between the blocks. 15 20 In its bottom wall 41 the part 40 is provided with an opening 49 shaped to receive the depending lip 37 at the forward end of the guide bar 23. To apply the part 40 to the housing 19 the part is arranged with its side walls 42 and 43 at opposite sides of the extending end of the guide bar 23 and then the part is forced upwardly to carry its side wall extensions 50 up into the recesses 38 and to dispose its bottom wall 41 at the underside of the projecting end of the guide bar, and 25 with the lip 37 of the guide bar disposed in the opening 49 in the bottom wall of the part. Thereafter, a suitable securing means as the pin 51 is passed through openings 52 in the side walls of the part and through the opening 39 in the body 19. In this way the part is rigidly secured in 30 place by the use of the one pin 51 or other means which may be removable since such pin prevents downward or outward movement of the upper portion of the part and the lip 37 entering the opening 49 locks the lower portion of the part against any movement outwardly relative to the body 19 or to the left as viewed in Figs. 1 and 6. 35 When the part 40 is in place the forward surfaces of the blocks 45 are spaced slightly from the forward end or face of the shear block 24 providing a raceway 53 below the guideway 30. The staples 62 fed along the guide bar 23 are fed one at a time into the raceway 53 below the plunger 31 and as will later be described means are provided to operate this plunger to drive the staples through the raceway. The strip of staples placed on the guide bar 23 is forced along the same in the direction of the raceway 53 by means of a 40 follower 54 which is shaped to straddle the guide bar and is normally urged forwardly therealong by a coil spring 55. This spring 55 surrounds a rod 56 the forward end of which is slideable in a sleeve 57 within the follower 54 and the forward end of the spring 55 bears against this sleeve. At its rear end the spring bears against a ring 58 on the bar 56 and the rear end portion of the bar may be carried upwardly as at 59 and then forwardly as at 60 and its free end may be hooked as at 61. This free end of the bar is re-

ceived in an opening 62a in the top wall of the elongated body 20 of the housing 19. (See Fig. 1.)

Obviously the spring 55 acting against the follower 54 tends to move it forwardly along the guide bar 23 and force the staple strip 62 along the guide bar toward the raceway 53. The follower mechanism may be removed by forcing the rod 56 forwardly and then moving its rear end portion upwardly to release its hooked end 61 from the opening 62a in the housing 20. Thereafter, it is but necessary to draw the rod 56 rearwardly and the entire follower mechanism will be removed from the housing. When a new staple strip is placed on the guide bar the follower 54 is placed over the guide bar and by forcing the rod 56 forwardly the follower is forced forwardly and the spring 55 compressed, the forward end of the rod 56 sliding through the sleeve 57 at the underside of the follower. The rod 56 is pushed forwardly until its end may be hooked in the opening 62a in the housing and this leaves the spring 55 compressed so that it is constantly urging the follower 54 forwardly along the guide bar. Forward movement of the follower 54 may be limited by a stop or lug 54a struck up from the top wall of the follower and adapted to engage a stop wall 19a in the housing or magazine 19.

The staple supporting housing 19 including the head 22 is pivotally mounted in the main housing 10 above the anvil bar 16 thereof. To this end the elongated body 20 is provided with depending ears 63 and a pin 64 passes through the side walls of the main housing 10 and through openings in said ears 63 and pivotally mounts the staple supporting housing 19 in the main housing 10. Staple guide bar 23 is secured in the housing 19 by screws 65 and 66 of which the screw 65 may include a relatively long head to form a stop limiting movement of the housing 19 in one direction about its pivot 64. In Fig. 2 the head screw 65 is shown as engaging the bottom wall 14 of the main housing and thereby limiting movement of the staple supporting housing relative to the main housing.

A handle 67 may be provided by extending the bottom and side walls of the main housing as shown. A second handle 68 is provided and intermediate its ends is pivoted to the main housing. The forward end 69 of the handle 68 extends into the housing 10 between the side walls thereof and a pivot 70 pivotally mounts said handle on the side wall of the housing. Also, within the housing 10 is an operating member or lever 71 pivoted on the side walls of the said housing as by a pivot 72 passing through the lever intermediate its ends. At its forward end lever 71 includes the reduced portion 73 which enters the opening 34 in the upper end portion of the plunger 31, and in its rear end portion said lever is provided with a slot 74 through which extends a pin 75 whereby the forward end of the handle 68 and the rear end of the lever 71 are connected by a pin and slot connection.

On its top wall 25 the elongated body 20 of the staple supporting housing is provided with a curved or dish-like recess or depression 76 located slightly forwardly of the pivot 64. In the rear of its pivot 70 the handle 68 is provided with a thickened portion 77 having a socket 78 therein, and it will be noted that the pivot 70 of the handle is forwardly with respect to the pivot 64 of the staple supporting housing and that depression 76 and the socket 78 are located so that their centers are between the centers of the 75

pivots 64 and 70. A cup-like member or housing 79 having a rounded end 80 is provided to enclose the spring 81, and this member has its rounded end seated or bearing in the depression 16 and the member is of a diameter to telescope into the socket 78. A relatively heavy spiral spring 81 is arranged between the handle 68 and the elongated body 20 of the staple supporting housing 19, and one end portion of this spring 10 is located in the socket 78 of the handle and the other end portion of the spring is received in the housing member 79.

The parts are shown in their normal positions in Fig. 2 where it will be noted that the longitudinal center of the spiral spring 81 is substantially vertical, and this spring serves to maintain the parts in the normal positions in which they are shown. That is, the spring pressing upwardly against the handle 68 maintains the 20 handle with its forward end 69 lowermost, and due to the pin and slot connection between the handle and the lever 71 the rear end of the latter is maintained lowermost and its forward end is maintained against the stop pin 82. Since 25 the forward end of the lever 71 is in the opening 34 of the plunger 31 obviously the plunger is normally held in a retracted position, and since the forward end of the said lever is forcing upwardly against the stop pin 82 it is exerting a lifting action 30 on the forward end of the staple supporting housing 19 maintaining said housing in position. The housing member 79 enclosing the spring 81 supports this spring and prevents its buckling or bending sideways and thus keeps it straight.

Assuming that a staple has been fed into the raceway and that some sheets of paper or the like P are to be stapled together, the handle 68 is rocked about its pivot in the direction of the handle 67 and the initial movement of the 40 handle 68 causes a compressing of the spring 81 and a lifting of the forward end 69 of the handle which owing to the pin and slot connection 74 and 75 raises the rear end of the lever 71. Therefore, this lever 71 is not exerting a lifting 45 action on the head 22 and the spring 81 is pressing downwardly on the staple supporting housing 19 forwardly of its pivot 64 so that the staple supporting housing is rocked about its pivot 64 in a direction to carry its head 22 toward the 50 anvil 18. This is as shown in Fig. 3.

On subsequent or further movement of the handle 68 in the direction indicated the forward end 69 of said handle continues to move upwardly and carries with it the rear or inner end of the 55 lever 71 so that the forward end of said lever must move downwardly. The head 22 by this time is against the documents to be stapled and cannot move downwardly further, and when the lever 71 is swung as indicated it moves the 60 plunger 31 downwardly in the guideway 30 to have its lower end portion move through the raceway 53 and drive the staple therefrom and clinch it against the anvil.

On the handle 68 being released the spring 81 65 returns the parts to normal position. This is accomplished by the spring forcing the handle upwardly to carry the forward portion of the handle downwardly and thus rock the lever 71 in a direction to have it exert a lifting force 70 on the head portion of the staple supporting housing 19 and return such housing to normal position in addition to retracting the plunger 31. Fig. 4 shows the parts in their extreme position and there it will be noted that the rounded end 75 80 of the member 79 has rocked on its seat in the

depression 16 so that the force compressing the spring 81 is in the direction of the longitudinal axis of the spring as the housing member 79 keeps the spring straight, and pressure of the spring is further to the left or forwardly of pivot 5 64 than when the parts are in the position of Fig. 1, so that the effective leverage of the spring on member 19 increases as the operating lever 68 moves downwardly.

From the foregoing it will be understood that 10 the spring is always straight and is compressed or expands always in the direction of its longitudinal axis and its effective leverage increases as it is compressed. The spring acts to throw the staple supporting housing 19 downwardly to move 15 its head 22 in the direction of the anvil, and the spring also serves to return the handle 68 and the other operating parts to their normal positions. For its entire length the spring is enclosed by the member 79 and the walls of the socket 78 20 so that the spring is prevented from bending, and is held straight and its only movement must be in the direction of its length. The rounded end 80 of the member 79 may rock or slide in the depression 16, and this shifting of the member 25 results in a shifting of the lower end of the spring so that the spring is always in a position where its action is in the direction of its axis.

The shear block is slotted or recessed in its forward edge as at 83 to accommodate the pawl 30 or dog 46 in certain of its movements. The purpose of this dig is to prevent a second staple from entering the raceway 53 until the first staple to enter the raceway has been driven therefrom. When a staple is in the raceway below 35 the lever of the top of the shear block 24 the connecting bar of the staple engages the front edge of the lower arm of the dog 46 and swings it from the position of Fig. 2 to that of Fig. 4 so that the upper lug portion 46a engages the 40 forward staple of the strip still on the guide bar and prevents another staple entering the raceway until the first staple has been forced from the raceway. This dog or pawl 46 constitutes a safety feature to prevent clogging of the machine 45 and is fully disclosed and claimed in my prior Patent 1,829,537 issued October 27, 1931.

Having thus set forth the nature of my invention, what I claim is:

1. In a plier type stapling machine, a housing, 50 a handle pivoted to said housing, a staple supporting housing pivotally mounted in the first housing and having a head provided with a raceway and a plunger operable to drive a staple therethrough, an anvil on the first housing below the raceway, a connection between the handle and plunger, a spiral spring between the handle and the staple supporting housing, a cup-like member embracing one end of the spring and having a pivot bearing on the housing, said 55 spring adapted on movement of the handle to rock the staple supporting housing on its pivot to move its head toward the anvil, and said handle on further movement adapted to operate the plunger to drive a staple. 60

2. In a plier type stapling machine, a housing, a handle pivoted to said housing, a staple supporting housing pivotally mounted in the first housing and having a head provided with a raceway and a plunger operable to drive a staple 70 therethrough, an anvil on the first housing below the raceway, a connection between the handle and plunger, a spiral spring between the handle and the staple supporting housing, a cup-like member embracing one end of the spring and 75

having a rounded end forming a pivot bearing on the housing, said spring adapted on movement of the handle to rock the staple supporting housing on its pivot to move its head toward the anvil, said handle on further movement adapted to operate the plunger to drive a staple, and said spiral spring operable to return the parts to normal position on said handle being released.

3. In a plier type stapling machine, a housing, a handle pivoted to said housing and having a socket, a staple supporting housing pivotally mounted in the first housing and at its forward end having a head provided with a raceway and a plunger operable to drive staples therethrough, an anvil supported by the first housing below the raceway, said staple supporting housing having a rounded depression in its upper side, a cup-like member having a rounded end resting in said depression, a spiral spring having its respective ends received in the cup-like member and the socket in the handle, said spring adapted on movement of the handle to rock the staple supporting housing on its pivot to move its head toward the anvil, and a connection between the handle and plunger whereby on further movement of the handle the plunger is operated to drive a staple.

4. In a staple driving machine, a staple supporting housing comprising an elongated hollow body, a guide bar in said body and extending through the forward end thereof, the forward end portion of said body including a guideway forwardly of the forward end of the guide bar, a staple driving plunger in the guideway, a removable block rigid with the housing and cooperating with the forward end of the guide bar to provide a raceway below the guideway, means locking this block against longitudinal movement 40 away from the bar, comprising interengaging shoulders on the bar and the block, means to feed staples along the guide bar to the raceway, and means to operate the plunger to drive the staples through the raceway.

5. In a staple driving machine, a staple supporting housing comprising an elongated hollow body, a guide bar in said body and extending through the forward end thereof, the forward end portion of said body including a guideway forwardly of the forward end of the guide bar, a staple driving plunger in the guideway, said guide bar having a depending lip at the underside of its forward end, a removable part secured to said housing and including a lower wall having 55 a recess receiving said lip, a pair of upwardly extending side walls engaging side wall portions of the housing, means securing said side walls to the housing, and a portion cooperating with the forward end of the guide bar to provide a raceway below the guideway, means to feed staples along the guide bar to the raceway, and means to

operate the plunger to drive the staples through the raceway.

6. In a plier type stapling machine, a housing, a handle pivoted to said housing and having a socket therein, a staple supporting housing pivotally mounted in the first housing and at its forward end having a head provided with a raceway and a plunger operable to drive staples therethrough, an anvil supported by the first housing below the raceway, said staple supporting housing having a rounded depression in its upper side, a member having a rounded end resting and rockable in said depression, a spiral spring having one end receiving in the socket in the handle and its other end bearing against said member, said spring adapted on movement of the handle to rock the staple supporting housing on its pivot to move its head toward the anvil, and a connection between the handle and plunger whereby on further movement of the handle the plunger is operated to drive a staple.

7. In a plier type stapling machine, a housing, a handle pivoted to said housing and having a socket rearwardly of its pivot, a staple supporting housing pivotally mounted in the first housing and at its forward end having a head provided with a raceway and a plunger operable to drive staples therethrough, an anvil supported by the first housing below the raceway, said staple supporting housing having a rounded depression in its upper side forwardly of its pivot, a cup-like member extending partly into said socket and having a rounded end resting in said depression, a spiral spring having its respective ends received in the cup-like member and the socket in the handle, said spring adapted on movement of the handle to rock the staple supporting housing on its pivot to move its head toward the anvil, and a connection between the handle and plunger whereby on further movement of the handle the plunger is operated to drive a staple.

8. In a staple driving machine, a staple supporting housing comprising an elongated hollow body, a guide bar in said body and extending through the forward end thereof, the forward end portion of said body including a guideway forwardly of the forward end of the guide bar, a staple driving plunger in the guideway, a removable block rigid with the housing and cooperating with the forward end of the guide bar to provide a raceway below the guideway, a spring pressed follower for feeding staples along the guidebar to the raceway, said block having an upright recess, and a dog pivoted in the recess shaped at its upper end to adapt it to engage the first staple of a strip on the bar and shaped below the pivot to be held in this position by a staple in the raceway to prevent a second staple entering the raceway while there is a staple therein.

FRIDOLIN POLZER.
